UNITED STATES PATENT OFFICE.

EARL C. GIRE, OF WHITTIER, CALIFORNIA.

DESIGN FOR A DIRECTION-SIGNAL-LAMP CASING.

Application filed October 18, 1922. Serial No. 4,018. Term of patent 3½ years.

To all whom it may concern:

Be it known that I, EARL C. GIRE, a citizen of the United States, residing at Whittier, in the county of Los Angeles and State of California, have invented a new, original, and ornamental Design for Direction-Signal-Lamp Casing, of which the following is a specification, reference being had to the accompanying drawing, forming part thereof.

Figure 1 is a front elevation of a direction signal lamp casing, showing my new design. Figures 2 and 3 are plan view and end elevation of the same respectively.

I claim:

The ornamental design for a direction signal lamp casing, as shown.

EARL C. GIRE.
